UNITED STATES PATENT OFFICE.

JOHN PEARSON, OF CHICAGO, ILLINOIS.

CAR CONSTRUCTION.

1,145,262.

Patented July 6, 1915.

Application filed November 13, 1911. Serial No. 660,136.

To all whom it may concern:

Be it known that I, JOHN PEARSON, a citizen of the United States, residing at Chicago, in the county of Cook and State of Illinois, have invented certain new and useful Improvements in Car Constructions, of which the following is a description.

My invention belongs to that general class of devices known as car construction or the like, and relates particularly to a draft arm construction for the draft rigging and buffer gearing for railway cars or the like.

My invention has among its objects the production of a construction of the kind described that is simple, durable, efficient, satisfactory and inexpensive, that may be employed wherever found applicable.

The construction is particularly applicable on steel railway cars, and its use is not confined to any particular car construction or style of draft or buffer rigging.

To this end my invention consists in the novel construction, arrangement and combination of parts herein shown and described, or uses mentioned.

In the drawings, wherein like reference characters indicate like or corresponding parts, Figure 1 is a side elevation of one end of the car center beam with the draft arm secured thereto. Fig. 2 is a plan view of the under side of the same. Fig. 3 is a side elevation of the center beam, illustrating how the same is cut away at each end. Fig. 4 is a cross sectional view taken substantially on line 4, 4 of Fig. 1, and Fig. 5 is a cross sectional view taken substantially on line 5, 5 of Fig. 1. Fig. 6 is a side elevation of a beam, showing the draft arm at each end, and Fig. 7 is a top plan view of the same.

Referring to the drawings, in which my preferred construction is shown, 1 is an I-beam which extends centrally through the car from end to end, the beam being provided with the usual flanges 2 and 3 at the top and bottom respectively. At each end of the beam a portion is cut away at 5 so as to leave an extending part 4 to the end of the car (see Fig. 3). Inasmuch as both ends of the beam are substantially similar, it is not considered necessary to illustrate both ends, nor is the complete car shown, but only those parts sufficient to illustrate the invention. Upon each side of the beam, at each end, is secured a draft arm plate 6, which

is preferably offset at the top as at 6¹, and at the end as at 6², and the offset portions flanged as at 7 and 8. The two arms are similar except that they are oppositely formed. The plate or flange 8 is further flanged at 9 to correspond with the flange 2 on the lower edge of the I-beam 1. The flange 9 preferably extends to the opposite end of the draft arm, as most clearly shown in Fig. 2, the same preferably dropping slightly below the flange 2 of the I-beam except at the end where it is preferably raised at the end as at 13. If desired, the end of the draft arms may be flanged as at 14. The two draft arms may be secured to the center beam in any desired manner, as for example by bolts or rivets, rivets being shown for the purpose. In assembling the arms, the same are arranged on each side of the beam with the extending flanges 7 extending along the end 4 of the beam, the beam being secured between the two flanges by the rivets 10, or their equivalents. The flanged end 8 is secured to the body of the beam 1 by rivets 11, or their equivalents for the purpose, and the flange 9 is secured to the flange 2 on the beam by rivets 12, or their equivalents.

As is obvious, the construction described, while extremely simple and comparatively inexpensive, is very rigid and satisfactory. The draft rigging and buffering gear are not shown, it being understood, however, that the same is of any suitable or preferred construction, and is arranged within the draft arms and carried thereby in any suitable manner. I have not shown any means for attaching the rigging or gear mentioned, inasmuch as this varies with the different styles. It may be mentioned, however, that the sides 6, 6 and tops 6¹ 6² of the arms form very convenient places for attaching the draft rigging and buffering gear, or their coöperating parts, the same being secured thereto in any suitable manner, depending upon the style of rigging or gear used.

It will thus be seen that it is a very practical construction of draft arm and center beam, and that all strain that comes on the draft arms will be transmitted to and taken up and shared by the center beam. The cost is moderate. The draft arms consisting of only two parts at each end, and the necessary rivets or bolts for securing them in position, and the center beam being only

changed by cutting away a portion of the lower edge, the parts are easily constructed and assembled.

Having thus described my invention, it is 5 obvious that various immaterial modifications may be made in the same without departing from the spirit of my invention, hence I do not wish to be understood as 10 limiting myself to the exact form, construction, arrangement or combination of parts herein shown and described, or uses mentioned.

What I claim as new and desire to secure by Letters Patent is:—

15 1. The combination in a car construction of an I-beam, having the lower portion of the web of the beam and its lower flange cut away at each end for a portion of its length, and a draft arm arranged on each 20 side of said beam at each end, each arm comprising an integrally formed plate extending parallel with the beam, with the lower edge disposed below the lower edge of the beam, each arm being transversely 25 offset at the top and at one end, and outwardly flanged at said offset portions and about its other edges, said flanged end portion flanged at the bottom to correspond with the top face of the lower flange of the 30 beam, said arms secured to each other and to the beam at the upper and end flanges of the arms and web of the beam and to the

lower flange of the beam at the ends of arms, with the opposite ends of the arms flush with the end of the beam.

35 2. The combination in a car of a center I-beam extending centrally the car from end to end, and a pair of draft arms arranged at each end of the beam, one on each side thereof, each of said arms being formed of 40 an integral piece of material laterally offset at the upper edge to form a top and at one end to form a closed end, and provided with flanges at said top and end, means for securing each of said arms at said flanges 45 to the web of the beam and to its lower flange at the end of the arm, the position of web of the beam and its lower flange between the arms being entirely cut away adjacent the juncture of the offset parts of 50 the arms with their flanges, the said arms being outwardly flanged about their lower edges and at the ends proximate the end of the beam, the outer flanged end of each of the arms being flush with the end of the 55 beam.

In testimony whereof, I have hereunto signed my name in the presence of two subscribing witnesses.

JOHN PEARSON.
